CLAIM

The ornamental design for a watering device, as shown and described.

DESCRIPTION

FIG. 1 is a perspective view of a watering device of our design;

FIG. 2 is a right side elevational view of the embodiment of FIG. 1 thereof;

FIG. 3 is a left side elevational view of the embodiment of FIG. 1 thereof;

FIG. 4 is a front side elevational view of the embodiment of FIG. 1 thereof;

FIG. 5 is a rear side elevational view of the embodiment of FIG. 1 thereof;

FIG. 6 is a top plan view of the embodiment of FIG. 1 thereof; and,

FIG. 7 is a bottom plan view of the embodiment of FIG. 1 thereof.

In this embodiment, portions shown in broken lines are for illustrative purposes and form no part of the claimed design.
